LOCK

Filed Sept. 20, 1928

UNITED STATES PATENT OFFICE.

EDWARD N. JACOBI, OF MILWAUKEE, WISCONSIN, ASSIGNOR TO BRIGGS AND STRATTON CORPORATION, OF MILWAUKEE, WISCONSIN, A CORPORATION OF DELAWARE.

LOCK.

Application filed September 20, 1928. Serial No. 307,188.

This invention relates to certain new and useful improvements in lock structures and has as an object the provision of an improved retainer for the lock bolt actuating spring whereby the same serves to secure the cylinder mounting head in its support.

A more specific object of this invention resides in the provision of a lock structure wherein a spring retainer for the locking bolt actuating spring yieldably projects beyond the circumference of the mounting head to engage in a recess in the door or other support in which the lock is to be mounted to thus secure the lock assembly in position.

Another object of this invention resides in the provision of an improved lock structure having a guide plunger which materially simplifies the installation of the lock and further serves to guide the longitudinal movement thereof as it is slid in and out to perform its locking function.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side elevational view, with parts broken away and in section, of a lock embodying my invention;

Figure 2 is an end elevational view of the lock assembly;

Figure 3 is a fragmentary view of the rear end of the lock with the mounting head in section and the cylinder locking bolt in side elevation;

Figure 4 is a perspective view of the inner end of the lock cylinder, locking bolt and washer member, and;

Figure 5 is a fragmentary view similar to Figure 3 illustrating the manner of assembling or disassembling the lock.

In the accompanying drawings, in which like numerals designate like parts throughout the several views, 5 represents a lock cyl-

inder mounting head which is centrally bored from the rear, as at 6, and has its outer end 7 provided with a smaller bore 8 concentric with the bore 6. A lock cylinder 9 is rotatable in the bore 6 and has a reduced outer end portion 10 which receives a protecting cap 11 rotatable in the reduced bore 6, the cap 11 having an annular flange 12 on its outer peripheral edge abutting a shoulder 13 at the junction of the bores 6 and 8 to prevent outward movement of the cylinder.

The cylinder is provided with a plurality of spring pressed tumblers 14 which are normally spring urged into longitudinal slots 15 in the walls of the mounting head bore to restrain the cylinder against rotation, the tumblers being retractable within the circumference of the cylinder upon the insertion of a proper key 16 in the usual key opening 17 extended therethrough.

Rotation of the cylinder by the key 16 operates to retract or extend the locking bolt 18 beyond the periphery of the mounting head, the locking bolt preferably consisting of a stamping having its locking end slidable in a recess 19 in the wall of the head in communication with the rear end of the bore 6. A shoulder 20 abuts the walls of the bore 6 to limit outward movement of the bolt under the influence of an expansile spring 21 confined between two spaced guide parts 22 on the inner end of the locking bolt with one end engaging a tit or enlargement 23 formed on the bolt and its other end engaged in a removable retainer 24 secured in a recess 25 in the wall of the bore 6 diametrically opposite of the recess 19.

The inner end of the cylinder has a substantially V or segmental shaped extension 26 from one end of which a cam 27 projects to engage a shoulder 28 on the inner end of one of the guide parts 22 so that rotation of the cylinder in a counterclockwise direction with respect to Figure 2, causes cam 27 to bear against the shoulder 28 and retract the bolt against its spring 21, the guide part carrying the shoulder 28 working in the cut away portion 29 of the lock cylinder which defines the segmental extension 26 and the other working on the outer face of the V or segmental shaped extension.

To prevent the insertion of an instrument through the key opening 17 to retract the locking bolt against its spring 21, a washer 30 is positioned between the cylinder and

locking bolt. The halves of the washer 30 are on different planes so that one half 31 engages the extension 26 and the other half 32 engages the cut away portion 29 thus effectively closing the key opening at its rear, a recess or cut away portion 33 in the washer member permitting the projection therethrough of the eccentric pin 27.

In assembling the lock, the cylinder is engaged in the bore of the mounting head from the rear, the washer member 30 is then positioned to engage the rear end thereof and the locking bolt unit is passed through an irregular shaped opening 34 in the wall of the mounting head opposite opening 19 and in register with recess 25. The spring 21 and retainer 24 are then secured in position in the manner illustrated in Figure 5, the well or cup 35 of the retainer projecting through the opening 34 beyond the periphery of the mounting head, for the reason later described. In assembling or disassembling the lock, a screw driver or other tool 36 is employed in the manner illustrated in Figure 5, disassembling being accomplished by prying the well 35 of the retainer out of the opening 34, as will be readily apparent.

The retainer 24 may be either milled from stock material, as illustrated in Figures 1 and 4, or stamped from bendable sheet metal, as illustrated in Figures 3 and 5. In either case, the top of the retainer has a flange 37 which fits within the recess 25.

The door or other support 38 in which the lock unit is to be secured is bored, as at 39, and has a recess 40 adapted to register with the cup 35 of the retainer when the lock is in position so that the cup 35 projecting beyond the mounting head engages therein to firmly secure the lock assembly in place. As is customary in structures of this character, the means securing the lock assembly in position is inaccessible as long as the device being locked is locked. In the case of an automobile or other door, the means securing the lock assembly in position is accessible from the outer edge of the door, which is protected when the door is closed, but when the door is open, a suitable instrument may be inserted through the recess 40 to free the lock cylinder and thus permit its ready removal for purpose of replacement or repair.

In structures where the lock is mounted for axial or longitudinal movement for the performance of its locking function, the plunger or cup member 24 functions as a guide for this movement in addition to retaining the same in position, as will be readily obvious, in which case the opening 40 is elongated to a depth equal to the movement of the lock in operation. The spring plunger 24 further greatly facilitates the mounting of the lock in its operative position as it is merely necessary to depress the same to withdraw it in the circumference of the mounting head 5

and engage it in its support, as will be readily evident.

What I claim as my invention is:

1. In a lock, a lock cylinder mounting head, a lock cylinder rotatably mounted in the mounting head, a locking bolt mounted in the mounting head, spring means normally yieldably urging the locking bolt beyond the circumference of the mounting head, a retainer for said spring normally projecting beyond the circumference of the mounting head, cooperating means between the lock cylinder and locking bolt whereby rotation of the cylinder retracts the bolt against its spring, and a support adapted to receive the mounting head and having a recess in which said spring retainer extends to secure the lock therein. 70

2. In a lock including a lock cylinder mounting head, a lock cylinder rotatably mounted in the head, a locking bolt retractable by the actuation of the lock cylinder and a spring normally urging the locking bolt to one position, a retainer for the spring and normally urged thereby to project beyond the circumference of the mounting head and being compressible within the circumference of the head. 80

3. In a lock including a lock cylinder mounting head, a lock cylinder rotatably mounted in the head, a locking bolt retractable by the actuation of the lock cylinder and a spring normally urging the locking bolt in one position, a retainer for the spring and normally urged thereby to project beyond the circumference of the mounting head and being compressible within the circumference of the head, and means limiting the movement of the retainer beyond the circumference of the head. 95

4. A lock assembly of the character described, comprising a mounting head having a central bore and a slot traversing the bore, a lock cylinder rotatable in the bore, a locking bolt slidably mounted in the slot and adapted to be inserted therein from one end, means limiting the movement of the locking bolt beyond the other end of the slot, an expansile spring engageable with the locking bolt and normally urging the same outwardly of the slot's other end, a retainer engageable with the other end of the spring and readily detachably positioned to retain the spring in operative position, a projection carried by the retainer and yieldably extended beyond the periphery of the mounting head for engagement in a recess in a support in which the lock assembly is mounted, and means whereby rotation of the lock cylinder actuates the locking bolt against its spring. 110

5. In a device of the character described, a lock structure mounted for movement in a support, a spring plunger yieldably urged to extend beyond the circumference of the lock structure to engage in a guide opening 120

in the support, and a locking bolt projectible beyond the circumference of the lock structure opposite said spring plunger to secure the lock structure against movement in the support.

6. In a lock cylinder of the character described, a mounting head, a support in which the mounting head is mounted for limited movement in the performance of the locking function of the lock, a guide carried by the support, a lock cylinder within the mounting head, a locking bolt operable by the cylinder, spring means normally tending to operate the locking bolt in opposition to the cylinder, said cylinder being key controlled to release the mounting head for movement in its support, and a retaining plunger for said spring means and yieldably urged thereby to extend beyond the circumference of the mounting head and engage the support guide to control the movement of the mounting head therein.

7. In a device of the character described, a lock structure including a mounting member movable in a support, a lock cylinder mounted in the mounting member and a locking member movable transversely in a mounting member opening to engage the support and restrain movement of the lock structure therein, said locking member being inserted in the mounting member opening through 25 one end thereof, spring means yieldably urging said locking member to one position, a retaining member for the spring means substantially closing the end of said opening through which the locking member is 30 inserted, and means carried by the retaining member and yieldably projected beyond the periphery of the mounting member to engage a guide opening in the support.

In testimony whereof I have hereunto af- 40 fixed my signature.

EDWARD N. JACOBI.
